UNITED STATES PATENT OFFICE

101,031

DESIGN FOR A TEXTILE FABRIC

Curt Erwin Forstmann, Montclair, N. J.

Application June 2, 1936, Serial No. 62,955

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design is a block-like pattern composed of series of rectangularly intersecting stripes, said series consisting of interrupted rows of irregular nubs elevated with respect to the background, the nubs of one series being larger than the nubs of the other, and the nubs of both series coalescing at the intersection.

I claim:

The ornamental design for a textile fabric as described and as shown.

CURT E. FORSTMANN.
